Attorneys.

UNITED STATES PATENT OFFICE.

CHARLES A. MOSGROVE, OF WATERBURY, CONNECTICUT, ASSIGNOR TO THE AUTOYRE COMPANY, OF OAKVILLE, CONNECTICUT, A CORPORATION OF CONNECTICUT.

SLIDE BUCKLE.

Application filed October 6, 1927. Serial No. 224,345.

This invention relates to buckles and especially to that type of buckles known as slide buckles used for adjusting the length of straps, webbing and the like, such as suspenders, and is so constructed as to secure the strap in adjusted lengths without penetrating the material and no stitching is required in attaching the buckle to the strap.

It is an object of the invention to provide a buckle of this type which is very simple in construction and may be made of a single piece of wire or rod, and which will securely hold the strap and not slip in operation when strain is applied thereto, and especially to provide a buckle of this type which is equally effective and will hold equally well on different thicknesses of webbing so that it is, therefore, not necessary to make as many different sizes of buckles and if the buckle is used on different thicknesses of webbing from that for which it was primarily designed it will not slip.

It is also an object of the invention to provide a buckle of this type which is so constructed as to allow greater space for passage of the double seam which is often used in suspender straps of overalls, and which may be threaded more easily.

A still further object is to provide a buckle structure which will not roughen or tear the edges of the fabric and which makes adjustment of the buckle much easier.

With the foregoing and other objects in view, I have devised the construction illustrated in the accompanying drawing forming a part of this specification. In this drawing,

Fig. 1 is a front elevation of the button loop end of a shoulder strap for overalls or the like showing my improved buckle applied thereto.

Fig. 2 is a longitudinal section substantially on line 2—2 of Fig. 1.

Fig. 3 is a longitudinal section substantially on line 3—3 of Fig. 1.

Fig. 4 is a plan view of the buckle removed.

Fig. 5 is a partial front elevation and partial section, the section being through the web just forwardly of one of the side bars of the buckle.

Fig. 6 is an end view of the buckle looking from the right of Fig. 4; and

Fig. 7 is an end view looking from the left of Fig. 4.

In the manufacture of overalls and the like garments the shoulder or supporting straps are usually made from scrap material such as scrap denim, and usually have a considerable taper as shown in Fig. 1. They also very often have a comparatively thick seam or fold along one longitudinal edge, and still further the thicknesses of the material used may vary considerably, some material being relatively thick and heavy and others being relatively light, and therefore, a buckle to be satisfactory should be able to accommodate itself to these different features and be equally satisfactory in spite of them. The present construction will work satisfactory on a tapered strap, with a strap having considerable thickness in the fold or seam, and will accommodate itself to a considerable range of thickness of material and at the same time may be easily threaded and also may be easily shifted for adjustment. In the drawing the strap or suspender 10 of any suitable material is shown with its free end looped through the eye of a button loop 11, and the body of the strap and the free ends thereof are reeved or threaded through the buckle as shown in Figs. 1, 2 and 3.

The specific construction of buckle shown comprises a single piece of square wire, although round wire or other material may be employed if desired, but the square wire is preferred because the corners give a better gripping effect on the fabric. The buckle comprises a central bar and two side bars spaced therefrom. The mid portions 12 of the side bars are substantially parallel with the center bar 13 but adjacent their opposite ends are inclined or curved outwardly as shown at 14, away from the central bar and are rounded as shown at 15, into the end bar 16 connecting the two side bars at one end of the buckle and into the end bars 17 connecting the side bars with the two elements of the central bar at the opposite end of the buckle, to thus provide in effect an open loop at the opposite ends of the buckle in the side bars and to produce an enlargement 18 at the opposite ends of the spaces between the side bars and the central bar. It is preferred that the side and the central bars be in substantially the

same plane as shown in Figs. 6 and 7, as this gives a flatter buckle which makes a smaller bulge in the fabric of the strap besides giving a better holding effect on the fabric. The end 5 bar 16 is offset or curved laterally as shown at 19, to permit the central bar to lie in substantially the same plane as the side bars, it being understood that the free ends of the central bar seat in the concave side of this 10 loop or offset.

It will be noted from Fig. 1 that the strap 10 has a pronounced taper but that is not objectionable in this buckle because the open loop at the opposite ends of the side bar and 15 the enlargement in the space between the side bars and the central bar at the opposite ends thereof will permit the side edges of the strap to fold inwardly as indicated in Fig. 5, if the width of the strap is somewhat greater than 20 the distance between the end bars of the buckle, and thus the extra width of the strap does not interfere with an easy movement 25 of the strap through the buckle as would be the case in a straight buckle. For this reason also the buckle does not roughen or tear the edges of the strap if it happens to be wider than the length of the buckle. Further as indicated in Figs. 1, 3 and 5, as these 30 straps are often made from scrap material there is considerable extra thickness caused by the double fold 20 along one side edge of the strap. The open loop, however, of the enlargement 18 easily accommodates this extra thickness as shown in Figs. 1, 2 and 5, and 35 therefore, this double fold does not interfere either with the threading of the strap through the buckle or the adjustment of the buckle on the strap. Still further the mid portions 40 of the side bars are spaced from the central bar a distance proper for the lightest or thinnest material for which the buckle is designed, and cooperation of these mid portions with the central bar will grip and hold on the thinner materials in the manner desired. If, however, a thick material is used 45 the loop portions at the end of the side bar permit the mid portions to yield sufficiently to accommodate this greater thickness of material. If the entire side bar were spaced 50 from the central bar equal to the distance of between the bars at the ends of the buckle then the spaces between the bars would be too great for the buckle to hold properly on the lighter materials and the buckle would 55 slip. Therefore, this buckle structure may be used on a greater range of thicknesses in the material of the strap than could a straight buckle. A further improvement of this 60 buckle over the straight buckle is that the enlargement 18 at the opposite ends of the spaces between the bars greatly facilitates the threading of the strap through the buckle in that the corner ends of the strap may be easily inserted through these enlargements.

65 As shown in Figs. 1, 2 and 3 the body of

the strap extends under the upper side bar through the space between this bar and the central bar, over the central bar and down through the space between the central bar and the lower side bar, and then under the 70 lower side bar to the button loop. The free end 21 of the strap is extended along the back of the buckle and forwardly through the space between the upper side bar and the central bar, then over this central bar between this bar and the body of the strap, and then back through the space between the central bar and the lower side bar, as indicated in Figs. 2 and 3. Thus strain on the 80 strap tightly clamps and holds the free end from slipping in the buckle and no stitching is required. It is preferred that the two central bars 13 be spot welded as indicated at 22, Fig. 4, to prevent their separating or pulling apart when very heavy denim is used, which 85 might prevent the buckle functioning properly.

Having thus set forth the nature of my invention, what I claim is:

1. A slide buckle including a pair of loops having side bars connected at one end and free at the opposite ends, intermediate bars extending from the free ends to and over the connecting member, the center portions of said side bars being substantially parallel with the intermediate bars and at their opposite ends extending outwardly away from the intermediate bars to provide enlargements in the opposite end portions of the spaces between the side and intermediate bars. 95
2. A slide buckle including an intermediate bar and side bars spaced laterally from the intermediate bar on opposite sides thereof, the said side bars being extended outwardly at their opposite ends to form enlargements in the opposite ends of the spaces between the bars. 105
3. A slide buckle including an intermediate bar and side bars spaced laterally from the intermediate bar on the opposite sides thereof, said bars being connected by end bars at their opposite ends, the side bars having their central portions substantially parallel with the intermediate bar and at their opposite ends extending outwardly away from the intermediate bar to form open loops with the end bars and of greater width than the distance between the central portions of the bars. 110

4. A slide buckle comprising a single length of wire bent laterally on opposite sides of its mid length to form side bars, the free ends being then bent inwardly toward each other and then at right angles to form an intermediate bar between the side bars, the mid portions of the side bars being substantially parallel with the intermediate bars and the opposite end portions of the side bars 125 being extended outwardly away from the in- 130

termidate bar to form open loops and enlargements at the opposite ends of the spaces between the bars.

5. A slide buckle comprising a single piece
6 of wire bent to form a pair of loops having side bars connected at one end and free at the opposite ends, and a pair of intermediate

bars extending side by side from the free ends to and over the connecting member, said intermediate bars being spot welded to prevent separation. 10

In testimony whereof I affix my signature.

CHARLES A. MOSGROVE.
